UNITED STATES PATENT OFFICE.

ROBERT A. SENTMAN, OF PHILADELPHIA, PENNSYLVANIA.

MACHINE FOR MAKING PAPER TUBES.

SPECIFICATION forming part of Letters Patent No. 377,643, dated February 7, 1888.

Application filed July 12, 1886. Serial No. 207,807. (No model.)

To all whom it may concern:

Be it known that I, ROBERT A. SENTMAN, a citizen of the United States, residing at Philadelphia, in the county of Philadelphia and State of Pennsylvania, have invented certain new and useful Improvements in Machines for Making Paper Tubes; and I do hereby declare the following to be a full, clear, and exact description of the invention, reference being had to the accompanying drawings, which form part of this specification, in which—

Figure 1 is a perspective of a machine embodying my improvements, and Fig. 2 is a perspective of details of reel.

15 My invention has for its object to provide a machine for constructing or producing paper tubes or cylinders, said machine being of such character that in operation a roll of paper is unwound and slit into strips, which are pasted, 20 folded, flattened, and wound in separate bolts or rolls, the said successive operations being effected without the employment of any gearing, and being dependent upon the draft produced on the paper in winding it in its flattened tubular form upon a reel at the final or 25 discharge end of the machine.

My improvements consist in the peculiar construction and combinations of parts, hereinafter fully described and claimed.

30 Referring to the accompanying drawings, A designates the frame of the machine, and B B standards thereon, affording supports for a spindle or shaft, C, which receives a roll of paper, which roll is designed to be converted into flattened tubes or cylinders.

D is a presser-roll, and D' a bar sustained on side supports, d d, which rest on the sills or side rails, a a, of the frame A.

E E are cutters, which may be ordinary 40 "shoe-makers' knives," comprising each a blade, e, and handle e'. The blades of the cutters pass through and are clamped in kerfs or openings e' in the cutter-board E', said board being sustained on uprights e'', that rest on the sills a.

E' is a leaf supported on and projecting rearwardly from the uprights e'.

45 G G are paste-rollers, all mounted on one shaft and dipping in the same trough, G', said 50 shaft having its bearings and said trough being supported on the sills a a of the frame A.

G' G' are pressure-rollers fitted on a shaft,

g', which has its bearings in the ends g' of a frame, G', that rests on the sills a a and is secured thereto.

55

H H are guides in the form of blocks, which rest upon the bed-piece A'. Said guide-blocks have their interior walls beveled or curved, so as to make flaring or tapering passages between them, there being a pair of these guides 60 for each strip of paper, as hereinafter explained.

I I are jacks, consisting of bars fulcrumed loosely on a transverse rod, I', sustained on supports I' on the frame A, and having at their 65 lower ends and on their under sides blocks i, which enter between the walls of the guides H H, as shown.

K and L are uprights duly supported on the frame A, and have openings, as shown, in 70 which are fitted rings or eyelets k and l. Said rings l are of less diameter than the rings k and in a more elevated plane than the latter.

M M are rings supported on an incline, M', resting upon the bed-piece A', in a plane 75 above that of the rings l, these rings M being of greater diameter than the rings k. The rings M are fitted on the board or support M', which is slotted at m m to receive and hold them clamped in position, so that one-half or 80 approximately one-half, or a section only, of each of said rings shall be above said board to form the channels through which the paper tubes are drawn and by which said tubes are partly compressed or flattened. These rings M 85 are vertically adjustable in their support, and may be depressed or elevated therein, so as to project more or less above the board, and thereby vary the diameters or widths of the passages which they form. Said rings M form gages for 90 the tubes and regulate the width which the latter will assume in formation, as said tubes will become in width equal to the greatest horizontal width or transverse line of the exposed parts of said rings or the parts thereof 95 above the board or support M'. To adjust the rings M downwardly, a tap of a hammer on their upper sides is sufficient, and they may be drawn upwardly by hand or the aid of a tool.

In operation said rings are in effect 100 half-round or segmental openings, the purpose of which is to compress or partly flatten the tubes to form guides for the latter and to regulate their width.

As only the upper parts of the rings M M operate directly on the tubes, it is not essential that said rings should be complete circles, and their lower parts, or parts below the upper 5 surface of the board or support M', may be of any convenient shape.

M² is a presser-roller having its bearings on standards m' m', supported on the sills a a.

N represents a reel whose shaft N' rests in 10 bearings in standards N² on the frame A. Said reel comprises two parallel blades, n n, secured to two radial arms, n' n', one or both of said blades being pivoted at one end and detachably secured at the other, so as to permit 15 it or them to be loosened and moved toward the shaft to allow removal of the tubes wound thereon, as hereinafter set forth.

In Fig. 2 is shown the detail construction of the reel N, the cross-bars n' n' being attached 20 to central hubs, n² n², having openings n³ n³ for the reception of the shaft N', which is detachably secured by pins n⁴ n⁴, passing through openings in it and in the hubs n² n². The blades n n are pivotally fastened by bolts to 25 one of the cross-bars n' and by pins to the other cross-bar, so that by removing said pins or one of them the blades or one of them may be moved toward the shaft to collapse the reel. The bars n' n' and blades n n may be said to 30 constitute the frame of the reel. To expedite work, several such frames may be provided, for which one shaft will answer, said shaft being easily taken out of one full frame by withdrawing the pins n⁴ n⁴ and inserting it and 35 them in an empty frame.

To fasten the ends of the paper tubes to the reel, one of the blades n of the latter is provided with a strip, n⁵, hinged at n⁶. The ends of the tubes are inserted between said strip 40 and its blade, and blocks or wedges n⁷ n⁷ then driven in between said strip and the shaft N'.

The operation is substantially as follows: The outer end of the roll of paper on shaft C is drawn under presser-roller D and bar D', 45 and thence against the knives E E, which latter cut it into long strips. Said strips are passed between the rollers G and G² and have lines of paste applied to their under sides and near one edge only, the rollers G² pressing the 50 strips against the rollers G while the latter apply the paste. The strips then pass between the guides H H and beneath the jacks I I, said guides and jacks giving to the strips a gutter shape, depressing them in the middle 55 and folding or turning their edges upwardly. These gutter-shaped strips now pass outwardly to and through the rings k and l, ascending as they proceed, the result being that they are still further folded, so that the unpasted edges 60 pass over and lap upon the pasted edges, thus forming tubes of cylindrical form. These cylindrical tubes are now drawn through the exposed or upper half or section of the rings M M, by which they are partly compressed or 65 somewhat flattened, and thence they pass beneath the presser-roller M², by which they are further or completely flattened. The ends of

the flattened tubes are now fastened securely to the reel N, and the latter revolved by means of a handle applied to the projecting end n⁸ of its shaft. The continued revolution of this shaft unwinds the paper from the roll on shaft C, draws it against the knives E E, by which it is cut into strips, and also draws these strips between the guides, under the jacks, through 70 the eyelets or rings, and under the final roller, M², whereby the paper in passing through the machine is converted from a wide web into a series of flat tubes, which latter are separately 75 wound upon a reel, the entire process being 80 accomplished without the employment of gearing and by means of draft applied to the paper itself. To remove the rolls of tubes from the reel, the latter is lifted off or out of its supports and the movable blade n loosened 85 and moved toward the shaft, whereupon said rolls can be readily taken or slipped off said reel.

I may here remark that I have found it essential or important to use a flat reel upon 90 which to wind the flattened tubes, as they cannot, according to my experience, be successfully wound into a small compass upon a round or circular reel.

The form of cutters employed—namely, 95 knives supported in a board—is an economic construction or arrangement, as the original cost of such knives is but slight and they can very readily be sharpened when dulled and replaced when worn out. So, too, said knives 100 can readily be adjusted by a mere downward tap on their handles to bring a fresh portion of their edges into alignment with the paper whenever required, the cutter-board in which said knives are supported clamping said 105 knives, so as to hold them steadfast when in operation, yet permitting their ready withdrawal and speedy adjustment whenever desired.

The paste and pressure rollers G G² are so 110 arranged that the paste is applied to the under side of the paper strips, the latter being pressed against the rollers beneath while such paste is being applied, so that just sufficient paste for the required purpose, and no more, is put on, 115 and when the strips are folded the original under side of the paper comes uppermost, the unpasted edges lapping over and upon the pasted edges.

The means for effecting the conversion or 120 transformation of the gutter-shaped strips (produced by the conjoint action of the guides H and jacks I) into tubular cylinders comprise only the two sets of rings k and l, which are inexpensive, yet very efficient, as are also the 125 rings or flatteners and gages M.

To prevent lateral movement of the strip n⁵—that is, a sidewise movement parallel with its blade—which would strain the hinge connecting said strip and blade, a staple, n⁹, may 130 be employed, said staple passing through openings formed for its reception in said strip and blade. This permits the strip to be freely moved on the hinge when necessary, yet keeps

it in alignment with its blade. Said staple is inserted from the shaft side, and cannot lose its position when the blade to which it is fastened is locked or fast.

5 What I claim as my invention is—

1. A machine for converting a web or roll of paper into multiple rolls of pasted and flattened tubes, said machine comprising, in combination, knives for cutting the paper into strips, rollers for applying paste to the strips, jacks and guides for channeling the strips, rings for folding the channeled strips into tubes and for flattening the same, and a flat reel for winding the tubes and drawing the paper completely through the machine, said parts being constructed and combined substantially as shown and described.

2. In a machine for forming paper tubes, the combination of jacks and guides whereby a preliminary or part fold is given to paper strips, with rings of different diameters progressively arranged in separate and independent series, whereby the channeled or partly-folded strips are caused to assume cylindrical form, substantially as shown and described.

3. In a machine for folding strips into tubes, and comprising means, substantially as described, for forming tubes into cylindrical form, the combination, with a support, M', of gages consisting of rings M, fitted therein so as to project partly above their support, said rings being vertically adjustable in their support to vary the extent of their projection, substantially as shown and described.

35 4. In a machine for forming flattened paper tubes, the combination, with means, substantially as described, for causing paper strips to

assume cylindrical form, of gages consisting of rings or eyelets having a portion thereof extending above the support and forming half-round or segmental passages or openings for partly compressing or flattening such cylinders, substantially as shown and described.

5. In a machine for forming paper tubes, the combination, with means, substantially such as described, for partly folding or channeling a strip of paper, of means for completely folding said strips or causing them to assume cylindrical shape and then to flatten them, such means consisting of two rings of different diameters and in different planes, and a half or partly exposed ring of greater diameter and on a higher plane than said folding rings, substantially as shown and described.

6. In a machine for forming paper tubes, the combination, with a reel-frame comprising blades n n and a fastening-strip, n⁵, of blocks or wedges n¹, substantially as shown and described.

7. In a machine for forming paper tubes, the combination, with a reel-blade, n, having a hinged or movable strip, n⁵, of a staple, n⁹, for preventing strain on the hinge connecting said blade and strip and for keeping said blade and strip in alignment, substantially as shown and described.

In testimony that I claim the foregoing I have hereunto set my hand this 8th day of July, 1886.
